(57) **CLAIM**

The ornamental design for the sole for a golf club wood, as shown and described.

DESCRIPTION

FIG. 1 is a perspective view of our new design for the sole or bottom surface of a golf club driver, the full outline of which is shown in phantom lines which form no part of the claimed design, throughout the figures;

FIG. 2 is a bottom plan view of the sole shown in FIG. 1 for a golf club;

FIG. 3 is a front elevational view of the sole shown in FIG. 1 for a golf club;

FIG. 4 is a toe side elevational view of the sole shown in FIG. 1 for a golf club;

FIG. 5 is a planar cross-sectional view taken along lines **5—5 FIG. 2**;

FIG. 6 is a planar cross-sectional view taken along lines **6—6 FIG. 2**; and,

FIG. 7 is a planar cross-sectional view taken along lines **7—7 in FIG. 2**.
